US0D1083688S

(12) **United States Design Patent** (10) Patent No.: **US D1,083,688 S**
(45) Date of Patent: ** Jul. 15, 2025

(54) **BICYCLE**

(71) Applicant: **Shenzhen yingfeinuo technology co., LTD**, Guangdong (CN)

(72) Inventors: **Huimin Fang**, Guangdong (CN); **Yifan Li**, Guangdong (CN); **Yizheng Lyu**, Guangdong (CN); **Shujian Chen**, Guangdong (CN)

(**) Term: **15 Years**

(21) Appl. No.: **29/983,635**

(22) Filed: **Jan. 10, 2025**

(51) LOC (15) Cl. **12-11**

(52) U.S. Cl.

USPC **D12/111**
